UNITED STATES PATENT OFFICE.

RALPH J. MEYER AND IRWIN A. MOON, OF GRAND JUNCTION, COLORADO.

PUMP.

1,186,114.

Specification of Letters Patent.

Patented June 6, 1916.

Application filed July 5, 1912, Serial No. 707,938.

Renewed November 13, 1915. Serial No. 61,445.

To all whom it may concern:

Be it known that we, RALPH J. MEYER and IRWIN A. MOON, citizens of the United States of America, residing at Grand Junction, in the county of Mesa and State of Colorado, have invented certain new and useful Improvements in Pumps.

Our invention has for its specific object improvements in rotary pumps.

10 In order to accomplish the object proposed, mechanism is employed consisting most essentially of a cylindrical casing and base-portion, furnished with inlet and outlet ports and provided with end-closures having shaft-bearings, extending transversely through their centers, whereto a shaft is journaled. On such shaft is fixed a cylindrical rotor, having a plurality of radial bucket-recesses, countersunk into the periphery thereof and disposed parallel to each other and to its axis. To the ends of the rotor circular heads are secured concentric therewith and peripherally contacting the curved interior portions of the casing. In 15 each recess in the rotor a bucket is housed, mounted on pivot-bearings in the heads, and adapted to swing outward into contact with the curved interior portions of the casing. The buckets are normally maintained in contact with the curved interior of such casing by means of springs. In the lower portion of the casing stationary cam-surfaces are provided for retiring the buckets into their recesses in the rotor and 20 for releasing them therefrom, at predetermined intervals. The cams are vertically adjustable, through a bolster located thereunder.

25 Referring now to the accompanying drawings, which form a part of this specification, Figure 1 is a transverse central vertical section of a pump embodying our improvements. Fig. 2 is a section of the same, at the line 2—2 in Fig. 1. Fig. 3 is an isometrical detail of the rotor, the buckets and one of the heads thereof. Fig. 4 is a section, at the line 4—4 in Fig. 1, of parts there shown. Fig. 5 is a sectional detail showing means whereby the heads are secured to the 30 rotor and the closures to the casing thereof.

Like reference characters indicate corresponding parts throughout the several views.

35 1 is a preferably integral cast casing, consisting of a segment of a cylinder 2 and base-portion 3 furnished with inlet and outlet ports 4 and 5 and provided with end-

closures 6 and 7 secured thereto and having shaft-bearings 8 and 9 extending transversely through the centers thereof. The bolster forms an abutment between the inlet 60 and outlet sides of the pump.

10 is a shaft journaled in the bearings 8 and 9 in the closures 6 and 7.

11 is a cylindrical rotor having a plurality of radial bucket-recesses 12 and 13, countersunk through the periphery thereof parallel to each other and to its shaft 10. 65

14 and 15 are circular heads, peripherally contacting the curved interior portion 2 of the casing 1 and secured concentrically to 70 the rotor 11, Fig. 5, by means of screws 16 extending through holes 17 in the former into sockets 18 tapped into the latter.

19 and 20 are a plurality of buckets—preferably approximately triangular in 75 cross-section—having inlet ports 21 and outlet ports 22 connected by means of conduits 23, wherethrough to admit water to and expel it from the bucket-recesses 12 and 13, and pivotally mounted, by means of trunnions thereon, in the bearings 25 in the rotor-heads 14 and 15.

26 are tension springs, connecting ears 27 and 28, on the rotor 11 and the buckets 19 and 20, respectively, and normally maintain the edges 29 of such buckets in contact with the curved interior of the cylindrical portion of the casing 1. 85

30 are cams—curved downwardly from and eccentrically to the axis of the rotor 11 90 to such an extent that the distance from such axis to the center points of the cams will equal the length of the radii of such rotor—for gradually retiring the buckets 19 and 20 into and releasing them from their respective recesses in the rotor at predetermined intervals, and are located in the base-portion 3 of the casing 1. They are preferably secured thereto by having their end-portions made fast in countersinks 31, Fig. 1, 100 in the curved interior of the cylindrical portion 2 thereof.

32 is a bolster having notches 33 formed in the top thereof to admit the central portions of the cam 30, which are fastened 105 thereto by means of screws 34. The under side of the bolster is beveled from its center toward its ends, and it is rendered adjustable vertically, by means of wedges 35 inserted between the latter and the base of 110 the cylinder.

36 are screws for maintaining the adjusted

wedges in any desired position on the base of the mechanism.

The employment of the connected inlet and outlet ports 21 and 22, in the buckets 19 and 20, insures instantaneous admission of water to and its expulsion from the spaces, in the recesses 12 and 13, back of the inner leaves *a* thereof, with the result that such buckets are thereby rendered very sensitive and responsive to the action of their springs 26, and with the further result that the friction between the edges 29 of the outer leaves *b* and the interior of the cylindrical portion of the casing 1 and cams 30 is reduced to a minimum.

In the operation of the pump, practically the only wearing surface is at the tips of the outer leaves *b* of the buckets. These being swung outward by the springs 26 cause the buckets to take up wear automatically which is an important feature, since no water is lost by the wear. Furthermore, the contact of the outer blades of the buckets with the casing is always very slight because of the fact that each bucket is balanced. The two leaves of the bucket are substantially equal in area, and a close joint is made between the edge of the inner leaf *a* and the base of the recess in the rotor, so that the head pressure cannot enter the spaces 12 and 13 behind said inner leaves, and the pressure of the load on the inner leaf is the same as that on the outer leaf. Consequently there is never at any time any friction between the tips of the buckets and the casing except that occasioned by the pull of the springs 26, no matter how strong the pressure worked against, and the entire weight of the load is borne at the close joint between the apex of the blades where the buckets are rounded to bear against the rotor. It is to be noted that there is no motion or change of position of the bucket while it is carrying the load, as the act of closing and opening one bucket takes place while the other one is carrying the load. Consequently the friction and wear on the buckets is reduced to a minimum, there being little or no pressure on them during the closing and opening part of the operation. The balanced bucket is important, because there is no more friction between the tips of the bucket and the casing under a heavy load than under a light load.

Assuming that power is applied to the shaft 10 wherethrough it is communicated to its rotor, which is being thereby driven in a direction indicated by the arrow, Fig. 1, and that water is entering the casing through its inlet port 4, the operation of the pump will be as follows: As the rotation continues,

the spring actuating the bucket 19 will cause its edges 29 to travel centrifugally outward, and as it traverses the contiguous portions of the cams 30, it will appropriate a part of the inflowing water and force the same upward and around through the space between the inner surface of the cylindrical portion of the casing and the periphery of its rotor, and thence discharge it through the outlet port 5 of the pump-casing. Each revolution of the rotor will result in two rapidly successive operations like the one just described.

Having fully described our invention, what we claim as new and desire to secure by Letters Patent is:—

1. In a rotary pump, in combination, a rotor having a plurality of bucket-recesses in the periphery thereof, heads closing the ends of the bucket-recesses, buckets having inner and outer leaves at an angle to each other and passages through said leaves to admit water to and expel it from the bucket-recesses and pivotally mounted therein by means of trunnions projecting from the ends of the buckets at the apex of the angle thereof into bearings in the heads of the rotor, substantially as described and for the purpose specified.

2. In a rotary pump, in combination, a rotor having a plurality of bucket-recesses at the periphery thereof, buckets comprising inner and outer leaves of substantially equal area pivotally mounted in the recesses and having inlet and outlet ports in said leaves connected by conduits located between the leaves, wherethrough to admit water to and expel it from the bucket-recesses, and springs for tilting the outer leaves of the bucket outward, substantially as described and for the purpose specified.

3. In a rotary pump, in combination, a rotor having a bucket recess in the periphery thereof, and a bucket pivotally mounted in said recess, the bucket having inner and outer leaves on opposite sides of its pivotal axis, the inner leaf being movable toward and from the rear wall of the recess as the bucket oscillates, the bucket also having passages extending through said leaves from the recess between the rear side of the inner leaf, and the rear wall of the recess to the rear side of the outer leaf.

In testimony whereof, we have hereunto set our hands this 18th day of March, 1912, in the presence of two witnesses.

RALPH J. MEYER.
IRWIN A. MOON.
